ABSTRACT OF THE DISCLOSURE

A process for detecting when a borehole enters a geopressed shale section utilizing the penetration rate of the drill bit as the measured variable. The penetration rate for the shale sections is plotted to determine the rate of change in the penetration rate, and the top of the geopressed section is detected by locating the depth at which the rate of change in the rate of penetration distinctly changes.

This invention pertains to a method utilizing drilling penetration rate data for determining where a well enters a section in which the fluid pressures exceed the hydrostatic head.

In many well drilling operations, it is desirable to determine the fluid pressure of the various formations penetrated by the borehole. For example, when wells are drilled in formations having fluid pressures that exceed the hydrostatic head for the depth of the formation it is necessary to take certain precautions to prevent undue damage from the abnormally high pressure. These formations are referred to as geopressure formations and are more fully described in a copending application of C. A. Stuart entitled "Drilling Geopressured Formations" filed April 6, 1964, Ser. No. 357,485. The cost of drilling a 15,000 foot well with 5,000 feet of geopressed section is frequently two to four times the cost of drilling a 15,000 foot well in a hydropressed section. This cost could be considerably reduced if it were possible to detect at what depth the borehole enters the geopressed section. Knowing where the geopressed section is penetrated would permit the use of normal drilling techniques until this penetration. The ability to use normal techniques for part of the well would considerably reduce the over-all cost of drilling the well. The added cost of drilling a geopressure well results from the increased cost of the drilling mud due to the requirement that it be heavier to contain the high pressures. The increased weight of the drilling mud often results in a decrease in the drilling rate and more frequent fishing jobs to recover stuck drill pipe. In addition the frequency of lost circulation is increased resulting in an increased number of junked wells. In addition to the increased costs of using heavier muds, costs are further increased by the necessity of employing heavier casing and additional strings of casing than are used in hydropressed formations. The use of a larger number of casing strings increases the possibility that the well will not reach its target depth before the casing becomes too small.

Accordingly, it is the principal object of this invention to provide a novel method for detecting where a well penetrates a geopressed formation prior to the penetration of a permeable reservoir within the geopressed formation.

Another object of this invention is to provide a unique method using drilling performance data to determine where a well penetrates a geopressed formation prior to the penetration of a permeable reservoir within the geopressed formation.

The above objects and advantages of this invention are achieved by determining the "normalized" rate of penetration of the drill bit through the shale formations traversed by the borehole. The measurements of penetration rate are made at frequent intervals during the drilling of the well and a plot of the penetration rate with depth is maintained. As the borehole enters the geopressed formations, the rate at which the "normalized" rate of penetration in the shale sections decreases with each increment of depth becomes less than the rate exhibited in the hydropressed formations. At this point, the penetration rate increases with respect to that which would be predicted from the rate of decrease in the hydropressed formations. The point at which the "normalized" rate of penetration in the shale sections increases indicates the penetration of the geopressed section. Thus, it is possible to drill the portion of the well above the geopressed section using normal drilling techniques and only the portion of the well which actually penetrates the geopressed section will require the high cost special techniques. This will result in an overall reduction of the drilling cost of the complete well.

The above objects and advantages of this invention will be more easily understood from the following detailed description of a preferred embodiment of the method when taken in conjunction with the attached drawing, in which:

FIGURE 1 is a schematic plot of the pressure gradient versus depth for the formations of the Texas-Louisiana Gulf Coast region of the United States, and a schematic plot of the pressure gradient versus depth of the drilling fluid in the borehole of a typical well drilled in this geographical location;

FIGURE 2 is a schematic plot of the differential pressure between the formations and the drilling fluid in the wellbore, and is derived from FIGURE 1;

FIGURE 3 is a schematic plot of the "normalized" rate of penetration in shale formations with depth for a complete well showing the change in penetration rate as the borehole penetrates the geopressed section;

FIGURE 4 is a drawing of a system capable of performing the method of this invention and

FIGURE 5 is a nomogram for normalizing drilling penetration rates.

Geopressed sections occur in many different geographical locations where it is desired to drill oil wells. One particular geographic location is the Texas-Louisiana Gulf Coast region of the United States that has tertiary shale formations of great thickness. These shale formations are usually deep water marine shales that contain few sand formations and are subjected essentially to a uniaxial compaction as a result of the compressive stress of the overburden.

In order for a shale formation to compact the fluids contained in the formation must be removed. The fluids can only be removed by flowing into sand formations or other permeable avenues of escape. Since the thick shale formations that occur in the Gulf Coast area have very few sand formations to act as avenues of escape the fluids are removed at a much slower rate than from thinner shale formations sandwiched between sand formations. This inability of the fluids to escape from the shale formations results in the creation of pressures within the formation that exceed the hydrostatic pressure for the depth of the formation. These excessive pressures are referred to as geopressures and the formations as geopressed formations.

The creation of geopressures within a shale formation can be more easily understood by considering the following conception of a shale model. The shale model is formed from perforated metal plates which are separated

by springs and water with the complete structure being enclosed within a cylindrical tube. The springs simulate the communication between the clay particles while the plates themselves simulate the clay particles. Upon the application of pressure to the uppermost plate the height of the springs between the plates remains unchanged as long as no water escapes from the system. Thus, in the initial stage the applied pressure is supported entirely by the equal and opposite pressure of the water. As the water escapes from the system through the perforations in the plate the uppermost plate will move downward slightly and the springs will carry part of the applied load. As more water escapes the springs will carry additional load until finally the complete axial load will be borne by the springs and the system will reach a state of equilibrium.

The clay particles forming a shale formation undergo a similar movement to that described above for the model when subjected to a uniaxial compaction due to the overburden. All formations are subject to an axial compaction but more permeable formations reach equilibrium much faster than shale formations. The inability of shale formations to reach equilibrium results in the occurrence of geopressed shales and geopresses in the fluids contained in permeable rocks which are enclosed within such shales. It can then easily be appreciated that the differential pressure between a column of drilling fluid of given density and the formation will be less in this case of geopressed formations than in the case of hydropressed formations.

Many mechanical factors affect the rate of penetration of the drill bit through shale formations including but not limited to, weight on the drill bit, rotary speed, drill bit diameter and design characteristics, drill bit wear, and drilling fluid circulation rate. The rate of penetration is also affected by the strength characteristics of the shale formations and the differential pressure between the column of drilling fluid and the shale formations. It is generally agreed within the petroleum industry that rate of penetration increases as the differential pressure decreases.

In order to utilize rate of penetration data to identify changes in differential pressure, all mechanical variables which influence rate of penetration should be equated to a common base, that is, "normalized" rate of penetration data should be used. The preferred method to "normalize" rate of penetration data is to hold all mechanical drilling variables and the mud density constant while operating the drill bit. With mechanical variables held constant, the rate of penetration is controlled primarily by the strength characteristics of the formation and the pressure difference between the mud column and the formation being drilled. In normally pressured shale formations, the strength increases with depth so that a gradual decrease in penetration rate will occur as a well is deepened. With constant mud density the pressure difference between the mud column and formation also increases as shown by FIGURES 1 and 2 causing additional decrease in penetration rate. When a geopressed shale is penetrated the pressure difference decreases sharply causing an increased rate of penetration which identifies the top of the geopressed section.

If it is not possible to hold mechanical drilling variables constant, an approximate method to "normalize" some of the more important variables is available by use of the equation

$$\frac{R}{60N} = \left(\frac{12W}{10D} \right)^d$$

wherein

R =rate of penetration, feet per hour

N =rotary speed, revolutions per minute

W =weight on drill bit, pounds

D =drill bit diameter, inches

d =empirical exponent required to equate left and right sides of equation

In this approach, the d exponent of the aforementioned equation is plotted versus depth in lieu of rate of penetration data as shown in FIGURE 3. Of course the above equation can be rewritten as

$$\frac{\log \left(\frac{R}{60N} \right)}{\log \left(\frac{12W}{10D} \right)} = d$$

10

Referring now to FIGURE 3 there is shown a schematic plot of the "normalized" penetration rate in shale formations versus depth for a well drilled into geopressed formations. The section of the curve 7 represents the portion of the well drilled in a hydropressed section.

At the point 8, the penetration rate changes and starts to increase. Point 8 then is the top of the geopressed section. The penetration rate then increases over an interval 9.

From the information plotted in FIGURE 3 it is easily appreciated that the point 8 which is indicated by an increase in the "normalized" penetration rate in shale formations denotes the point at which the borehole entered the geopressed section. Thus, it would be possible to drill the well using normal techniques until the depth indicated by the point 8 was reached. At this point it would be necessary, of course, to adapt the techniques used for drilling the geopressed wells.

30 The data shown in FIGURE 3 is for a single geological age, for example, the Miocene. Other geological ages, such as the Oligocene or the Eocene will have similar characteristics but slightly different values. These values can easily be determined by utilizing the method of this invention.

Referring now to FIGURE 4 there is shown a well that penetrates a hydropressed section 10 and enters a geopressed section 11 while the interface between the two sections is shown at 12. Of course it should be remembered that there is no sharp definition between a hydropressed and a geopressed formation, but rather a change from one to the other over a few feet. The well is shown as having a surface casing 13 installed for the first few hundred feet of the well and then a protective liner 14 that is installed so that it completely cases off the hydropressed formation 10 and extends into the geopressed formation 11. The drilling of a well and setting of surface casing and protective liner are more fully described in the above-referenced copending application of C. A. Stuart. The well is drilled by means of the conventional rotary bit 15 that is rotated by means of a drill string 16. The drill string extends to the surface where it passes through the conventional well head 21 that includes the blowout preventers and other equipment well known to those skilled in the art of rotary well drilling. The drill string 16 is rotated by means of a rotary table 16. The upper end of the drill string is coupled to swivel joints 17 that has a U-shaped bail member 19 attached thereto. A portion of the weight of the drill string is supported by the hook 20 which is moved by the drilling rig not shown in FIGURE 4.

The depth of the well of course is related to the length of drill string extending into the well and may be determined by means of a calibrated wheel 22 which is rotated by the travel of the drill string 16 into or out of the well. The calibrated wheel 22 may be coupled to a conventional selsyn unit in order that the depth of the well can be converted to a related electrical signal. Similarly, the weight on the drill bit 15 is determined by a transducer assembly 23 which determines the hook load on the drilling rig 20. The hook load can be related to the weight on the drill bit 15 by subtracting the hook load as determined by the transducer from the total weight of the drill string. Conventional equipment is available 70 for converting the hook load to an electrical signal W

that represents the weight on the drill bit 15. The depth of the well bore as determined by the calibrated wheel 22 is supplied to a time depth computer 24 which also receives an electrical signal 25 that represents time. The signal representing time can be obtained from a suitable clock mechanism or may be obtained directly from commercially available 60-cycle AC power. The time depth computer 24 then divides the depth by time to obtain a signal R representing the rate of penetration of the drill bit. The signal R is supplied to an operational amplifier 30 that also receives a signal N by means of a lead 27, wherein N represents the speed of the rotary table 16. The operational amplifier 30 divides R by N and supplies the result to an operational amplifier 31. The operational amplifier 31 adjusts the product by a factor K_1 wherein K_1 represents 1 divided by 60. The operational amplifier 31 supplies the adjusted product to a logarithm converting unit 32 that converts the product to a related logarithm. In a similar manner a signal W representing the weight on the drill bit is supplied to an operational amplifier 33 that also receives a signal D representing the diameter of the drill bit. The signal D may be represented by a variable potential that is manually adjusted for changes in the drill bit. The operational amplifier 33 divides W by D and supplies the result to an operational amplifier 34. The operational amplifier 34 adjusts the product by a factor K_2 wherein K_2 represents 12 divided by 10^6 . The operational amplifier 34 supplies the adjusted product to a logarithm converting unit 35 that converts the product to a related logarithm. Both of the related logarithms are supplied to an operational amplifier 36 that divides the two logarithms and supplies a signal related to d . The operational amplifier 36 is coupled to a chart recorder 38 by a lead 37 in order that the value of d may be recorded. The chart recorder is driven by a signal related to the depth of the well and thus the record is related to depth. The record 39 illustrated in FIGURE 4 is related to the well shown and thus indicates an increase in the penetration rate at a point 40. The point 40 corresponds to the top 12 of the geopressure formation 11.

While an analog system has been described above for normalizing the penetration rates obviously other systems such as digital systems could be used. Likewise a range of values for the various terms could be plotted in a logarithm form on a monogram and value of d obtained. A suitable monogram is shown in FIGURE 5 with a representative solution for one set of data. To use the monogram there must be available the rate of penetration, the rotary speed, bit weight and bit diameter. These factors are either known or can readily be determined by equipment that is normally available in the rotary drilling art. Assuming that the rate of penetration is 20 feet per hour and the rotary speed is 100 r.p.m., these values are plotted on the two left hand scales in FIGURE 5 and a line drawn between the two values. This line is extended until it crosses the third scale where the value for $R/60N$ is obtained. Next the bit weight and bit diameter are plotted on the two right hand scales and a line drawn between the plotted values. When this line is extended the value of $12W/10^6D$ is obtained; a line connecting the value of $R/60N$ and $12W/10^6D$ provides the value of the exponent d or 1.65 for the example shown. The monogram of FIGURE 5 permits the rapid obtaining of normalized values of the drilling penetration rate that may be plotted as shown in FIGURE 3. As explained above when the penetration rate increases it indicates that the borehole has penetrated the geopressured formation.

Normally the drilling rate is slow enough to permit the use of the monogram of FIGURE 5 and hand plotting of the values of d to detect the penetration of geopressed formation. Thus, the expense of a complete computer system to calculate the value of the exponent d can be avoided.

We claim as our invention:

1. A method for detecting the depth at which a borehole enters geopressured shale sections, said method comprising:
  - measuring a rate of penetration property of only shale sections penetrated by the borehole;
  - recording said measured rate of penetration property of the shale sections with relation to depth;
  - determining from said recording the rate of change in said rate of penetration property and detecting the top of the geopressed shale section by locating the depth at which said rate of change distinctly changes.
2. A method for detecting the depth at which a borehole enters geopressured shale sections, said method comprising:
  - "normalizing" mechanical drilling variables including, but not limited to, weight on bit, rotary speed, bit size circulation rate and mud density of maintaining all such variables constant;
  - recording the resultant rate of penetration in shale formations with relation to depth of the drill bit; and detecting the top of the geopressed shale sections by locating on the recording the depth at which the rate of decrease of said rate of penetration distinctly changes.
3. A method for detecting the depth at which a borehole enters geopressured shale sections said method comprising:
  - "normalizing" mechanical drilling variables including but not limited to weight on bit, rotary speed, bit size and circulation rate in a manner that establishes a "normalized" rate of penetration in which the effects of mechanical variables are essentially removed;
  - recording the result "normalized" rate of penetration in shale formations with relation to the depth of the drill bit; and
  - detecting the top of the geopressed shale sections by locating on the recording the depth at which the rate of penetration distinctly changes.
4. An improvement in the process of drilling a well by rotating a drill bit, circulating a drilling fluid, and casing the walls of the borehole, said improvement comprising:
  - initiating the drilling employing a drilling fluid and a casing program designed for fluid pressure substantially equaling the hydrostatic head corresponding to the depth of the borehole;
  - measuring a rate of penetration property of the shale formations penetrated by the borehole;
  - determining the rate of variation with depth of the rate of penetration property of the shale formations encountered by the well;
  - determining the top of the geopressed shale section by locating the depth at which said determined rate of variation undergoes a change in the direction of an anomalous lack of decrease in penetration rate with depth; and
  - resuming the drilling employing a casing program and a drilling fluid designed for fluid pressures significantly greater than the hydrostatic head corresponding to the depth of the borehole.
5. A process for detecting the depth at which a borehole enters geopressured shale sections, said process comprising:
  - measuring the weight on the drill bit, rotary speed, bit size;
  - measuring the rate of penetration property of only the shale sections penetrated by the borehole;
  - correcting the measured rate of penetration property of the shale sections for variations in the measured weight on the drill bit, rotary speed and bit size;
  - plotting the corrected rate of penetration property of the shale sections with relation to depth; and
  - detecting the top of the geopressed shale sections by locating on the plotted record the depth at which the rate of change in the corrected rate of penetration distinctly changes.

6. The process of claim 5 wherein said measured rate of penetration is corrected by converting it to a d exponent, wherein said d exponent is obtained from a nomogram having penetration rate and rotary speed plotted to a log scale at one side and bit weight and bit size plotted to a log scale at the opposite side, said d exponent being plotted to a log scale at the center of the nomogram.
